Primary Examiner—Alan P. Douglas*Assistant Examiner*—Clare E. Heflin(74) *Attorney, Agent, or Firm*—Joseph J. Previto(57) **CLAIM**

The ornamental design of a foldable hand tool, as shown and described.

DESCRIPTION

FIG. 1 is a plan view of the foldable hand tool showing my new design in the unfolded position;

FIG. 2 is a view taken along the line 2—2 thereof;

FIG. 3 is a view taken along the line 3—3 thereof; and, FIG. 4 is plan view of the foldable hand tool showing my new design in the folded position.

The broken lines shown on the drawings are for illustrative purposes only and form no part of the claimed design.
